PUTTING HOLE

Louis M. Davis, Cleveland, Ohio

Application April 1, 1955, Serial No. 498,667

2 Claims. (Cl. 273—177)

The present invention relates to a target or "hole" for putting practice and for miniature golf sets for home use.

An object of the invention is the provision of an inexpensive target which simulates as closely as possible an actual hole.

The invention contemplates avoiding any "uphill" ramps or surfaces in the vicinity of the actual target itself. Previous articles of the same general class have been provided which avoid such ramps or surfaces by providing resilient fingers suspended from a frame, the fingers being arranged in a circle having a diameter about equal to the diameter of a golf hole. The bottom of the fingers is spaced somewhat less than golf ball height above the level surface representing the rim of the hole. Accordingly, the ball must brush by these fingers to get either in or out of the hole. This arrangement avoids ramps or other inclined surfaces but does not satisfactorily duplicate the effect of an actual hole because whether a ball rolls completely over an actual hole or drops in the hole depends on the ball's velocity, but the ball is admitted over the rim of the hole in the incoming direction without any resistance whatsoever.

Accordingly, an object of the invention is to provide a structure which is easy to enter and harder to leave, no matter what direction it is approached by the ball, thus simulating the necessity of approaching a real hole at low speed. A particular object of the invention is to accomplish this without any springs or spring-loaded members or other elaborate and costly devices.

Still another object of the invention is to further refine the above improvements by approximating the rim-riding or cornering effect of an actual hole, which effect reduces the chances of sinking a ball which enters tangentially rather than centrally.

These and other objects and advantages of the invention will be readily understood from the following description of the presently preferred specific embodiment of the invention.

In the drawings:

Figure 1 is an isometric view of a device embodying the invention.

Figure 2 is an elevational view of the device shown in Figure 1, with one part removed for greater clarity. Alternate positions of certain parts are shown in phantom view. The device is shown in association with a golf ball, successive positions of which are also shown in phantom view.

Figure 3 is a detail isometric view of a certain portion of the structure shown in Figures 1 and 2.

The illustrated device comprises a plurality of upright legs 10 terminating at their tops in stubby transverse T-stubs 11. The legs 10 are joined by a ring 12 which is welded or brazed or otherwise suitably fastened to the legs at the points 13.

The adjacent halves of each adjacent pair of T-stubs 11 constitute a pair of fixed hinge pins on which is supported one of a plurality of hinging members 14. Each

2

hinging member 14 preferably comprises a single piece of light sheet metal or other suitable material which is bent slightly outwardly as along a line 15 and which has a pair of side flanges 16 in each of which is formed a generally vertically extending short slot 17 of a sufficient size to receive with a loose and sloppy fit an associated hinge pin 11. The lower edge of each hinging member 14 is spaced above floor level a distance slightly less than golf ball height.

Each hinging member 14 can swing inwardly freely about its associated pair of hinge pins. Outward swinging movement is limited, however, by engagement of the edges of the associated pair of side flanges 16 with the ring 12, the member 14 being preferably so shaped and proportioned that this engagement occurs before any other portion of the member 14, such as the gable or fold line 15, engages the ring 12.

Thus, as shown in Figure 2, a ball may approach the device as indicated at A. As the ball contacts the hinging member 14 on the incoming side, the member swings freely inwardly. Thus, as the ball reaches position B, the hinging member 14 is in the dotted line position shown. The hinging member 14 on the incoming side continues to hinge freely inwardly to fully admit the ball, after which such member swings back to its initial position.

The ball continues through the "hole" as shown in its solid line position C. As it contacts the hinging member 14 on the outgoing side, this member starts to swing outwardly. When the ball reaches the position D, the hinging member 14 on the outgoing side is in the illustrated phantom position, at which point the flanges 16 associated with this member 14 contact the ring 12. The member 14 is then wedged upwardly by the forward upper portion of the ball, the slots 17 accommodating this lifting of the member 14 by the ball. If the momentum of the ball is sufficient, the member 14 will be lifted completely out of the way, and the ball 14 will pass through the "hole" as indicated at E, the hinging member returning to normal position.

The outwardly bent shape of the hinging members 14 accentuates the mechanical advantage which the ball has when striking these members from an angle rather than head on. Thus, if the ball strikes the outgoing hinging member after having passed through a relatively short chord of the "hole," the ball will require less momentum to escape than if it had struck the hinging member head on. This approximates the rim-riding or cornering effect of an actual hole in which a tangentially-entering ball is less likely to sink than a centrally-entering ball.

It will be seen that the frame of the device comprising the legs 10, T-stubs 11 and ring 12 is a simple assembly. The remaining parts comprise the identical hinging members 14. Final assembly comprises merely slightly folding the hinging members, which may be slightly resilient, to allow the flanges 16 to be slipped into slot-engaged contact with the T-stubs 11.

The disclosed embodiment of the invention may be varied in details not essential to the invention. The scope of the invention is not to be limited to these details but is to be defined by the following claims.

What is claimed is:

1. A golf ball hole simulating device comprising a plurality of hinging elements arranged to define a regular polygon, hinge means for said elements for providing for hinging movement of each of said elements about a horizontal axis into and out of said polygon, said elements depending from said hinge means, support means for said hinge means, said elements and said support means being so proportioned that when said support means is placed on a level surface the lower edges of said elements are spaced slightly less than golf ball height above said sur-

face, means for limiting outward swinging movement of said elements at a point before the lower edges of said elements exceed golf ball height above said surface, said hinge means including means for accommodating slight upward movement of said elements relative to said support means to a point where the lower edges of said elements exceed golf ball height above said surface, whereby a golf ball is easily admitted to the projection of said polygon on said surface but must wedgingly lift one of said hinging elements in order to leave the area of said projection.

2. A device according to claim 1 in which each of said elements is bent outwardly at central portions across its width.
